UNITED STATES PATENT OFFICE.

FREDERICK HAROLD HARRIS, OF GATESHEAD, ENGLAND, ASSIGNOR OF ONE-HALF TO
ISAAC EDMUND WALTON, OF GATESHEAD, ENGLAND.

VALVE.

1,280,216.

Specification of Letters Patent.

Patented Oct. 1, 1918.

Application filed December 4, 1916. Serial No. 134,924.

To all whom it may concern:

Be it known that I, FREDERICK HAROLD HARRIS, a subject of the King of England, residing at Low Fell, Gateshead, in the county of Durham, England, have invented a new and useful Improved Valve, of which the following is a specification.

This invention relates to valves for internal combustion, steam, air and other gas or vapor engines, of the annular or ring type which are moved axially to uncover the inlet and exhaust ports in the cylinder walls and so control the admission and emission of working fluid to and from the cylinder. 15 The present invention has for its object to provide an improved arrangement of superposed or end-to-end valves.

According to the invention I employ a plurality of ring valves arranged one close above the other at the top or at one end of the engine cylinder the interior surfaces of the valves forming a continuation of the interior surface of the cylinder, one of said valves seating upon the cylinder wall and 25 the other valve or valves seating upon the next lower valve, said valves controlling the inlet and exhaust ports opening directly into and out of the engine cylinder. I also provide mechanical means whereby one or more 30 of said valves can be lifted or moved axially to uncover the inlet port or ports or the exhaust port or ports in the wall of the engine cylinder.

I will fully describe my invention with 35 reference to the accompanying drawings wherein:—

Figure 1 is a central vertical section of the head or upper portion of the cylinder of an internal-combustion engine fitted with my 40 improved arrangement of ring valves and with one construction of means for operating same in accordance with my invention; and Fig. 2, is a plan on the line X—Y in Fig. 1.

Referring to the drawings, *a* is the engine 45 cylinder, *b* the piston, *c* the inlet for working fluid which opens into an annular chamber *d* in the cylinder casting, and *e* the outlet to exhaust which leads from an annular chamber *f* in the cylinder casting. In the 50 embodiment of my invention illustrated in the drawings, I provide two valves *g*, *h* each of which comprises a complete ring, the internal diameter of which is the same as that of the engine cylinder *a*, and thus is very 55 slightly greater than the external diameter

of the piston *b*. The interior surfaces of the ring valves *g* and *h* form a continuation of the interior surface of the cylinder wall. The lower ring valve *h* is provided with an inclined or beveled under face *j* seating on a 60 beveled face *k* around the cylinder, and forms the wall between the exhaust passage *f* and the interior of the engine cylinder *a*. The upper ring valve *g* is also provided with an inclined or beveled under face *m* 65 and seats on the upper face *n* of the lower ring valve *h* which is similarly inclined. The upper valve *g* forms the wall between the inlet passage *d* and the interior of the engine cylinder. The cylinder head *o* which 70 carries the usual spark plug *p*, is made so that it can be readily detached from the cylinder casting *a*, and, in order to render the upper ring valve *g* gas-tight, I provide a split junk or like packing ring or rings *q* 75 arranged in an annular recess or groove *r* in the cylinder head. While the under faces of the ring valves *g* and *h* are shown as being beveled, it will be obvious that, if desirable, the under faces of these valves may 80 be horizontal or at right angles to the axes of the cylinder.

To open the engine cylinder *a* to working fluid or to exhaust the ring valves *g* and *h* are lifted off their seatings by rods *s* and *t* 85 attached at diametrically opposite points to the ring valves *g* and *h*. In the arrangement illustrated in the drawings, the rods *t*, which are attached to the upper valve *g*, are hollow and surround the rods *s* attached to the 90 lower valve *h*.

The rods *s* and *t* may be lifted at predetermined intervals by any convenient means. For example, and as shown in the drawings, the rods *s* project beyond the upper ends of 95 the hollow rods *t* and are connected together by a cross bar *u*, the rods *t* being similarly connected together by a cross bar *v* which is cranked so that its center portion lies alongside the cross-bar *u*, said cross bars 100 being alternately lifted by cams *w*, *x* mounted side by side on a cam shaft *y* suitably driven from the crank shaft of the engine. Springs *z* are provided in boxes *2* to return the valves to normal position after they have been lifted, said springs being arranged between collars 105 *3* on the rods *t* and inner ends of screw plugs *4* which close the boxes *2*. It will be seen that, when the upper valve *g* is lifted, the 110

- lower valve *h* is not moved and the inlet passage *d* only is put into communication with the interior of the cylinder *a*, while, when the lower valve *h* is lifted, the upper valve *g* is also lifted with it, but the port in the cylinder wall communicating with the inlet passage *d* is still covered by the valve *h* and the exhaust passage *f* only is put into communication with the interior of the cylinder
- 10 *a.* In some cases, instead of arranging the actuating rods *s* and *t* one within the other as above described I may arrange them side by side, or otherwise conveniently and may provide separate springs for returning each valve to normal position.
- 15 The ring valves *g* and *h* combine the advantages of the mushroom and sleeve types of valves as they give a large area of opening with a small lift, the opening extending 20 completely around the engine cylinder. The valves are cheap and simple to construct and readily fitted, and, by removing the cylinder head, direct access can be had to the valves thus permitting easy repair. Moreover, a 25 perfectly cylindrical combustion chamber is obtained, and, when used with steam or air

engines, a very small clearance space is required.

I claim:

1. A plurality of ring valves arranged 30 one above the other at one end of an engine cylinder, the interior surfaces of the valves forming a continuation of the interior surface of the cylinder, one of the said valves seating upon the cylinder wall and the next 35 superposed, said valves controlling the inlet and exhaust ports, opening directly into and out of the engine cylinder, substantially as herein described.

2. The combination with a plurality of 40 end-to-end ring valves, of mechanical means for lifting said valves, said means consisting of actuating rods attached to the rear of the ring valves and passing through spring-loaded boxes to the outside of the engine 45 cylinder, the rods attached to each ring valve being coupled together by a cross-bar adapted to be lifted by a cam on a cam shaft operated from the crank shaft of the engine, substantially as and for the purpose herein 50 described.

FREDERICK HAROLD HARRIS.
